DESK SET

Filed May 31, 1928

Fig. 4.

INVENTOR.
Walter F. Benson

UNITED STATES PATENT OFFICE

WALTER F. BENSON, OF ST. PAUL, MINNESOTA

DESK SET

Application filed May 31, 1928. Serial No. 281,939.

The invention relates, generally, to improvement in desk sets, and the invention has reference, more particularly, to a desk set of the type used to hold fountain pens. The invention is an improvement of a device of the same general purpose shown in the United States application filed by me December 23, 1927, Serial No. 242,035.

The invention has for its principal object, 10 to provide a novel desk set, that allows for a full universal movement of the pen holding tube.

It is a further object of this invention to provide holding means to retain the pen 15 holding tube in any position.

It is also an object of this invention to provide a desk set, having frictional means that will hold the pen retaining tube upright and that will not interfere with a free radial 20 movement of said retaining tube.

It is another object of this invention to provide a desk set that may be cheaply constructed from material readily obtainable.

Other objects of this invention, not at this 25 time particularly enumerated, will be clearly understood from the following detailed description of the same.

With the various objects of this invention in view the same consists, primarily in the 30 novel desk set for holding fountain pens hereinafter set forth, and the invention consists, furthermore, in the novel arrangements and combinations of the various devices and parts, as well as in the details of the construction thereof, all of which will be hereinafter more fully described in the following 35 specifications, and then finally embodied in the claims appended thereto.

The invention is clearly illustrated in the 40 accompanying drawing, in which:

Fig. 1 is a sectional view of the desk set on line 1—1—Fig. 2.

Fig. 2 is a sectional view of the desk set on line 2—2—Fig. 1.

Fig. 3 is an elevational view of the ball and ring.

Fig. 4 is an elevational view of the cup.

As shown in the drawing, I provide a suitable base 10, having a recess 12 on its upper surface, which provides a seat for post 14.

The post 14 is held in place by the screws 16—16. The upper inner edge of the post 14 is rabbeted to provide an annular groove 18, which constitutes an article seat for shoulder 20 of the cup 22. The ring 28 is forced into the enlarged portion 24 of the cup 22, the upper edge 26 of cup 22 is rolled against bevel 30 of ring 28, locking ring 28 securely to cup 22. The ball 32 is hingedly connected to the ring 28 by a pin 34 which passes through the ball and ring as shown in Fig. 1. The ball 32 is also provided with a stop pin 36 which limits the movement of the pen holder 38. The pen holder 38 is secured to the ball 32 by a screw 40 which passes through the lower end of said holder and through the spacing tube 42, said screw 40 having threaded means for engaging the ball 32. The pen holder 38 is mounted on one side of the center of the ball 32, as shown in Fig. 2 and Fig. 3 to allow 70 the pen holder 38 to be placed in a horizontal position when not in use. The pen holder 38 is held in upright position by the combined action of the friction between the ball 32, 75 tube 44 and the pressure of spring 46.

The entire cup and ball assembly is held in place by the retaining ring 48.

The upper surface 50 of the plate 44 can be covered with leather or other suitable material to help hold the ball in position. 80

The pen holder can be raised or lowered to any position and it will be held there by the plate and spring. This will not interfere with a free radial movement as the entire cup and ball assembly can swing freely 85 within the post.

It will, of course, be understood that various changes may be made in the form, details, proportions and arrangements of the parts without departing from the scope of my invention, which generally stated, consists of a device capable of carrying out the objects above set forth, such as shown, described and defined in the appended claims.

I claim:

1. A desk set, including a base, a tubular member projecting upwardly from the base and having an annular groove at the upper end of its interior, a cup in said member having its upper end formed with an annular 100

outwardly extending offset engaged in said groove, a ring seated within said offset, the upper end of the cup being bent over to engage the ring so as to hold same in the offset, 5 a retaining ring on the upper end of said member extending over the ring, a ball in the ring, a pin extending through the ball and ring to pivotally mount the ball, means in the cup engaging the ball to tension same, 10 an eccentric stop carried by the ball and engageable with the lower side of the ring to limit pivotal movement of the ball, and a pen holder secured to the ball.

2. A desk set including a base, a tubular member projecting upwardly from the base and having an annular groove at the upper end of its interior, a cup in said member having its upper end formed with an annular outwardly extending offset engaged in said groove, a ring seated within said offset, means to hold the ring in the offset, a ball in the ring, means to pivotally connect the ball to the ring, means to tension the ball, a stop on the ball engaging the ring to limit pivotal movement of the ball, and a pen holder carried by the ball.

3. A desk set including a base having a hollow part, a ring in said part, a ball in the ring, means to pivotally mount the ball, 20 a stop carried by the ball and engageable with the ring to limit pivotal movement of the ball, and a pen holder secured to the ball.

4. A desk set including a base having a hollow part, a ring in said part, a ball in the ring, means to pivotally mount the ball, a stop carried by the ball and engageable with the ring to limit pivotal movement of the ball, a pen holder, a spacing sleeve engaged with the base of the pen holder and with the ball, and a screw extending through the base of the pen holder and through the sleeve and threaded into the ball.

5. A desk set including a base having a hollow part, a ring in said part, a ball in the ring, means to pivotally mount the ball, a pen holder secured to the ball to one side of the pivotal means thereof, and a stop carried by the ball and disposed on the opposite side of the pivotal means thereof and engageable with the ring to limit pivotal movement of the ball.

6. A desk set including a base having a hollow part, a ring in said part, a ball in the ring, means to pivotally mount the ball, a pen holder secured to the ball to one side of the pivotal means thereof, and means to tension the ball.

7. In a desk set, a base, a tubular member projecting upwardly from the base, a ball in the tubular member, means to pivotally mount the ball, a pen holder, a spacing sleeve engaged with the base of the pen holder and with the ball, and a screw extending through the base of the pen holder and through the sleeve and threaded into the ball.

8. In a desk set, a base having a hollow part, a cup in said hollow part, means to mount the cup for rotary movement, a ball in the cup, means to pivotally connect the ball to the cup, means in the cup to tension the ball, and a pen holder connected to the ball.

9. In a desk set, a base, a ball, means formed to receive the ball therein, means to pivotally connect the ball to said receiving means, means to mount the receiving means for rotary movement relative to the base, and means within the receiving means to tension the ball so as to hold same in its various pivoted positions.

In testimony whereof, I affix my signature.

WALTER F. BENSON.
